PERMANENT WAVING DEVICE

François R. Marcel, Brooklyn, N. Y.

Original application September 3, 1931, Serial No. 560,979. Divided and this application January 4, 1933, Serial No. 650,086

10 Claims.

(Cl. 132—36)

The present case is a division of my application filed on the 3rd day of September 1931 and serially numbered 560,979, and patented January 17, 1933, No. 1,894,624.

5 My present invention relates to devices for producing what are known as permanent waves in the human hair, whether in the detached form such as switches or transformations, or upon the human head. In the production of what is known as a permanent wave, it is customary to apply a chemical to a lock of hair and to wind the hair upon a curler or pin and the pin and the lock of hair wound thereon are enclosed in a member or tube and subjected to heat.

10 Usually moisture is applied directly to the hair and it is more or less vaporized during the baking process. When the hair has been subjected to the baking process while under tension on the curling pin, its shape is permanently set so that the wave or curl therein, even though subjected to shampooing, is permanent in the sense that it remains until new hair grows out from the head and replaces the portion which has been waved. In most, if not all of the electrical processes heretofore used, it has been customary to carry on the heating operation to a point where all of the moisture or vapor has been driven out of the device in order to make the wave permanent. This has disadvantages because if the operator keeps the heat on for an appreciable time after the moisture has been driven out of the device, the hair is apt to be scorched or burned and in that way permanently injured.

15 It is difficult to know when the operation has been carried to the desired point because the hair is not visible while in the device. The operator generally has to attend to a number of waving devices distributed around the head and they are not ordinarily all started at the same time and with the same amount of moisture. The hair in one heater will therefore be dried at a different moment to another and the operator has difficulty in carrying the heating process to the extent of driving off all the moisture and terminating the heating operation before the hair has been injured.

20 One object of the present invention is to provide a device wherein steam is generated by means of an electric heater applied to the exterior of the device. Although the electric heater is not in itself new, I have provided a device wherein the steam may be heated to a high degree to form what might be called more or less dry steam, and this may be heated to such a degree as to cause 25 the hair to be set in a permanent wave without

dissipating all of the steam from the device and without carrying the baking operation to a point where the hair is entirely dry.

With the present device it is possible to prevent any liquid from touching the hair directly and allowing only the moisture in the vapor state to reach the hair. It is also possible to prevent the vapor, once generated, from condensing into liquid until the process has been completed.

Another object of the invention is to provide a device having the above characteristics and in which what is known as the Croquignole wave may be produced in permanent form.

Another object of the invention is to provide a device for producing permanent Croquignole waves by having a tubular member provided with a cross member or head in which the pin on which the lock of hair is wound may be disposed at right angles to the tubular member.

Another object is to provide a device for producing the Croquignole permanent wave and having a tubular member over which the ordinary electric heating element may be applied for producing the heat within the device for baking the hair, so that while the device is adapted to produce permanent Croquignole waves, it may be used in connection with the ordinary cylindrical electric heaters now in general use in connection with machines heretofore used for producing the helical waves.

20 With this arrangement hairdressers may be equipped with the Croquignole apparatus without discarding, but by making use of, the electrical equipment including the cylindrical heaters with which they have heretofore been equipped for the helical wave. This avoids the necessity of dispensing with expensive equipment with which hairdressers are now equipped in order to be supplied with apparatus for producing the Croquignole wave. It also permits the ordinary cylindrical electric heaters, to be used either for the helical wave or the Croquignole wave so that special heaters are not required for the Croquignole wave. It is even desirable in many cases to produce both the helical and Croquignole waves on the same head of hair and this is facilitated where the ordinary type of heater can be used for both the helical and Croquignole waves.

25 Another object is to provide a device which will drive the steam or vapor to the end of the device nearest the head in order to affect all parts of the lock of hair which is within the device and at the same time prevent the steam or vapor from passing out of the device near the head and striking the scalp. In this way injury to the scalp is avoid-

ed and it is also possible to avoid uncomfortably heating the scalp.

Another object of the invention is to provide a simple device made of rubber and connected with the heating tube near the head end for closing upon the lock of hair and preventing the hot vapors from passing to the scalp. Other objects of the invention will be set forth in the following detailed description.

10 In the drawing forming part of this application, Figure 1 is an elevation of a hair waving device embodying my invention, showing the same in position for waving a lock of hair,

15 Figure 2 is a sectional view taken on the line 2—2 of Figure 1,

Fig. 2^a is a sectional view of the upper portion of the tubes showing the closure member.

Figure 3 is a sectional view taken on the line 3—3 of Figure 2,

20 Figure 4 is a view similar to Figure 2 but showing a modified form of rubber connecting member,

Figure 5 is a sectional view taken on the line 5—5 of Figure 4, and

25 Figure 6 is an elevation of a clamping member for clamping the neck of the rubber member about the lock of hair.

The heating device wherein the hair is heated or baked consists primarily of an inner tube 1 disposed lengthwise within an outer tube 2 and the inner tube may be provided with embossings or raised portions 3 to engage the interior of the tube 2 and retain the two tubes spaced apart with an annular space 4 between them. The outer end 30 of the tube 1 may be closed by a removable plug 7' the same as in my said patent. The plug 50 to which the tube 1 is connected forms a closure for this tube at the end which is directed away from the head. The plug 50 has an aperture 51 which allows vapors to pass from the annular space between the tubes 1 and 2 into the bore of the plug which is controlled by the removable plug 7'. The electric heater 5 shown in the drawing is of the type commonly used in electric waving 40 machines which are arranged to produce a helical wave; and, as stated above, the present device for making what is known as the Croquignole wave is adapted to receive the same type of heater by having it passed over the outer tube 2 until it 45 abuts against the external bead 6 formed on the outer tube 2, which acts as a stop to limit and determine the final position of the heater 5.

It will be understood that the ordinary type of heater 5 has an opening through its center which permits it to be passed over the tubular member 2. The heater is not shown in detail because it is one of the well known heaters extensively used in electric hair waving. It is sufficient to say that it contains a coil of resistance wire to which current is fed through the cable 7 for the purpose of producing heat within the heater which, in this case, will act upon the tube 2 over which it is placed to generate steam or vapor within the waving device.

65 There is a connecting member 8, preferably of insulating material such as fibre and provided with a tubular portion fitting over one end of the tube 2. This member flares outwardly into a head 9 which is elongated or oval in section as shown in Figure 3. It has a projecting lip 10 around its open end or the end which is farthest from the tube 2.

70 There is a flexible rubber connecting member 11 which has a flange 12 to be fitted over the bead 10 of the head 9 to secure these members together.

This rubber member also has an enlarged end or flange 13 which is shown as secured around its edge to a pad member 14 corresponding with the pad member shown in my said co-pending application, except that it is longer in one diameter than the other to conform more nearly with the lock of hair and winding pin and with the shape of the head 9.

75 The intermediate or neck portion 15 of this rubber connecting member is adapted to be clamped upon the portion of the lock of hair which passes through it, by means of the clamp shown in Figure 6. This clamp consists of two jaws 16 pivoted to each other at 17 and provided with opening jaws 18 to permit the device to be passed over the neck portion 15 of the rubber member 11.

There is a locking member 19 which engages in the notch 20 and serves to hold the jaws closed upon the rubber neck of the connecting member.

20 In the formation of the Croquignole wave a winding pin such as is shown in Figures 2 and 3 is employed and upon which the lock of hair is adapted to be wound. The winding pin shown in the drawing is of well known form and consists of a body portion 21 usually reduced in diameter 25 at its middle portion and it is provided with a pivoted arm 22 which is adapted to close against the end of the lock of hair as the same is applied to the middle of the pin.

30 The operator starts by applying the free end of the hair to the middle of this pin and swings the member 22 so that it presses the end of the lock of hair against the body portion of the pin 21 whereupon the winding pin is revolved so that the lock of hair winds around the pin and the member 22 and builds up in spiral form upon the pin and upon itself.

35 The clamping arm 23 which is pivoted on the pin 21 is then swung over against the hair which is wound on the pin. The shield shown at the 40 left in Figure 2 is to protect the scalp during the waving operation and it preferably consists of the disc 14 of fibre or other relatively stiff material having a slot 24 extending across the center of the disc. This disc is secured around the 45 outer edge of the member 13 of the rubber connecting member either by cementing or by stitching it thereto, or both. There is a pad of softer material 25 such as felt, and it is secured to the left hand face of the member 14 in Figure 2, 50 such as by the same stitches which secure the member 14 to the member 13. This soft material has a slot 26 extending across its axis but at right angles to the slot 24 of the member 14, all as shown in my said co-pending application. 55

In using this form of device a lock of hair is combed out from the head and the free end is passed through the pad 25 and its backing member 14 and through the rubber connecting member 11, these several parts being detached from the head 9 while this operation is being carried out. The clamping member 16 is also removed from the rubber connecting member while the hair is being passed therethrough.

65 The curling pin 21 is wound on the portion of the lock of hair which has been passed through the rubber connecting member 11 and when the lock of hair has been wound upon the curling pin the latter, with the hair wound thereon, is inserted into the oblong chamber 27 of the head 70 9, whereupon the flange 12 of the rubber connecting member is fitted over the bead 10 of the member 9 so that the soft rubber member is in this manner connected with this head.

75 Around the tube 1 there is a moisture carrier

or absorbent material 28 which is supplied with moisture before the baking operation begins. Assuming the above operations have been completed, the clamping device shown in Figure 6 5 will be applied to the intermediate or neck portion 15 of the rubber connecting member by causing the arms 16 to straddle this member and then pressing the arms toward each other and finally swinging the locking member 19 over to 10 engage in the notch 20. This clamping member will then clamp the intermediate portion 15 of the rubber connecting member tightly against the lock of hair to prevent the passage of vapor or steam to the left in Figure 2 beyond the chamber 27 so that the steam or vapor cannot reach the scalp but can reach all parts of the hair that are on the winding member 21.

The electric heater 5 may now be placed over the outer tube 2 until it rests against the bead 6. 20 Current may now be turned on to cause the electric heater to generate heat.

The air in the concentric space between the tubes 1 and 2 will first be heated and gradually the liquid in the pad 28 will be heated to a point 25 where it is vaporized. This vapor or steam will pass from the inner tube into the chamber 27 of the head and circulate around the lock of hair which is on the curling pin.

It will be understood that any well known waving solution may be applied to the lock of hair 30 before it is closed within the chamber 27, the same as in other processes of waving hair. When the heating operation has been carried to a point where the wave is permanently set in the hair, the electric heater may be removed and the parts 35 of the waving device may be disassembled in the reverse order to that just described; that is to say, the rubber member 11 may be detached from the head 9, the clamp 16 may be removed from the neck of the rubber connecting member, and the lock of hair may be unwound from the pin 21. The lock of hair may be then withdrawn through the rubber connecting member, whereupon the entire device will be removed from the 40 hair.

In the present device the liquid is vaporized and it is completely circulated around the lock 45 of hair and the waving operation may be completed without reducing the hair to a dry state, thereby avoiding injury to the hair.

In Figures 4 and 5 I have shown a modified form of rubber connecting member lying between the head of the device and the scalp of the person whose hair is being waved. The connecting member 50 55 30 is shown as provided with a thin wall flange 31 which engages over the flange 32 of the insulating member 33, which performs the same function as the member 8 in the first described form. The rubber connecting member 60 has also a flange 34 which is adapted to receive and hold therein the pad 35, 36 which corresponds with the pad 14 and 25 of the first described form of the invention.

The neck portion 37 of this rubber connecting member has a relatively thicker wall in which an oval shaped opening 38 is formed for the passage of a lock of hair. Around this neck portion is attached a spring clamp as shown in Figure 5. This is in the form of a spring surrounding the 65 70 neck 37 and having loops 39 pressing against one side of the neck 37 and other loops 40 pressing against the opposite side of the neck and at points which are staggered in relation to the loops 39. The ends of this spring, shown at 41 75 are brought out nearly parallel to each other and

there is a locking member 42 pivoted to one of these ends and provided with a cam lever 43 for pressing on the opposite end of the spring to tighten the spring around the neck member 37.

When the lock of hair is passed through the aperture 38 and the spring is applied to the neck of the rubber member the loops 39, 40 of the spring press on opposite sides against the neck but at different vertical planes and they compress the neck snugly against the lock of hair 10 and form a close fit between the neck 37 and the hair for the purpose of preventing vapors from passing through the connecting member and against the scalp of the person.

It will be observed that by forming a tubular generating chamber for receiving the electric heater 5 thereover, that the ordinary types of heaters heretofore used in making the helical wave are readily adapted for heating the chambers 4 and 27. By arranging the elongated head 20 25 8 with the chamber 27 having its longest diameter at right angles to the annular space 4, the device is readily adapted for the forming of the well known Croquignole wave. In other words, it is not necessary to provide a special type of 25 heater for forming the Croquignole wave. The present device is interchangeable with the helical waving devices insofar as the heaters are concerned.

In some cases helical waves may be formed by 30 the means shown in Figures 1 and 2 of my said co-pending application for some of the locks of hair on a given head, and the device shown and described herein may be simultaneously used for other locks of hair on the same head where the 35 Croquignole wave is desired.

All of this may be accomplished while using the ordinary type of electric heater which has heretofore been provided for the helical wave alone. Most hair dressers are equipped with this type of 40 45 heater and it is therefore not necessary to discard the expensive equipment in order to form the Croquignole wave.

The rubber connecting member shown in Figures 1 and 2 is more or less spread out, whereas 45 in actual use the members 12 and 13 may be pressed close together in order that the length of hair between the curling pin and the scalp may be as short as possible in order to have the hair waved as near as possible to the scalp.

Having described my invention, what I claim is:

1. A device for waving the hair upon a person's scalp, including a tubular member adapted to receive thereover the ordinary cylindrical heater, means arranged at one end of said tube to form an elongated chamber extending at right angles to said tube and adapted to receive and hold therein a lock of hair wound upon a pin, and means adapted to be arranged between said pin and the scalp for co-operating with the lock of hair to prevent vapor from passing from said elongated chamber to the scalp.

2. A device for waving the hair upon a person's scalp, including a tubular member adapted to receive thereover the ordinary cylindrical heater, a member formed of heat insulating material and attached to one end of said tube, said member forming an elongated chamber disposed at right angles to said tube with the interior of said chamber in communication with the interior of said tube, said chamber being adapted to receive a winding pin with a lock of hair wound thereon disposed at right angles to the axis of said tube, and means for co-operating with the lock of hair 70 75 80 85 90 95 100 105 adapted to be placed between said chamber and said scalp to prevent vapors within said chamber from passing to the scalp.

3. A device for waving the hair upon a person's scalp including a tubular member adapted to receive the ordinary cylindrical heater thereover, a member formed of heat insulating material disposed at one end of said tubular member and forming an elongated chamber disposed at 10 right angles to said tubular member, with said chamber in communication with the interior of said tube, and a rubber connecting member detachably connected to the open side of said elongated chamber member, said elongated chamber 15 adapted to receive a winding pin with a lock of hair wound thereon and disposed at right angles to said tubular member, said rubber connecting member adapted to have a lock of hair passed therethrough to be wound upon said winding pin, 20 a protecting pad mounted on said rubber connecting member to lie adjacent the scalp, and means for clamping said rubber connecting member closely upon the lock of hair between said elongated chamber and said protecting pad, to 25 prevent vapors in said chamber from passing to the scalp.

4. A device for waving the hair upon a person's scalp, including a tubular portion adapted to receive thereover the ordinary cylindrical heater, 30 an absorbent liquid holding member in said tubular device, means connected with one end of said tubular device to form an elongated chamber at right angles to said tubular device, said chamber adapted to receive a winding pin with a lock of hair wound thereon and disposed at right angles to said tubular device, and a rubber connecting member detachably mounted on said elongated chamber member, said rubber member adapted 35 to have a lock of hair passed therethrough, and means for clamping said rubber member against the lock of hair to prevent the escape of moisture from said chamber to the scalp.

5. A device for waving hair, including a tubular member having a member at one end of heat insulating material, a rubber member having a pliable flange portion adapted to be fitted onto 45 said connecting member and having a flange of pliable rubber for holding a shield, and a neck portion between said members of relatively thick 50 rubber having an elongated aperture therethrough through which a lock of hair is adapted to be passed, and means for compressing said relatively thick portion against the lock of hair where it passes therethrough.

55 6. A device for waving the hair upon a person's scalp, including inner and outer tubes, and means for holding them in spaced relation to provide an annular chamber between the tubes, the inner tube having the end which is disposed away from 60 the person's head closed, and its opposite end in open communication with said annular chamber, said device having a head of oblong shape disposed crosswise of the axis of said tubes and providing a chamber adapted to receive a curling pin 65 therein, laterally of the axis of said tubes, said

chamber in said head being in communication with the interior of said tubes, means for preventing the escape of vapor from said chamber toward the person's head from which the lock of hair extends, and means for applying heat to 5 said device.

7. A device for waving the hair upon a person's scalp, including inner and outer tubes, and means for holding them in spaced relation to provide an annular chamber between the tubes, 10 the inner tube having one end in open communication with said annular space, said device having a head of oblong shape disposed crosswise of the axis of said tubes and providing a chamber adapted to receive a curling pin therein, laterally 15 of the axis of said tubes, said chamber in said head being in communication with the interior of said tubes, means for preventing the escape of vapor from said chamber toward the person's head from which the lock of hair extends, and 20 an electric heating device adapted to be applied to the exterior of said outer tube for the purpose of heating said waving device.

8. A device for waving the hair upon a person's scalp, including inner and outer tubes, and means 25 for holding them in spaced relation to provide an annular chamber between the tubes, the inner tube having one end in open communication with said annular space, said device having a head of oblong shape, composed of heat insulating material, disposed crosswise of the axis of said tubes and providing a chamber adapted to receive a curling pin therein laterally of the axis of said tubes, said chamber in said head being in communication with the interior of said tubes, means 30 for preventing the escape of vapor from said chamber toward the person's head from which the lock of hair extends, and means for applying heat to said device.

9. A device for waving hair, including hollow 40 means for receiving therein a lock of hair to be waved and means for heating said device, an end member for said device composed of pliable rubber having means for attaching the same to said waving device, and having a neck portion through 45 which a lock of hair is adapted to extend, and means for compressing said neck portion against a lock of hair to prevent the escape of vapors through said end member and comprising a spring surrounding said neck portion and having 50 loops pressing on opposite sides of said neck portion to compress the same against a lock of hair.

10. A device for waving hair including hollow means for receiving therein a lock of hair to be waved, and means for heating said device, an end 55 member for said device composed of pliable rubber having means for attaching the same to said waving device and having a neck portion provided with an elongated opening therethrough to receive a lock of hair, a spring member having 60 loops engaging opposite sides of said neck portion, the loops on opposite sides of said neck being staggered in relation to each other, and means for tightening said spring on said neck portion.

FRANCOIS R. MARCEL. 65
